[57] ABSTRACT

Novel fluoran compounds such as 2-bis-(5',6',7', 8'-tetrahydro-2'-naphthylmethyl)amino-6-diethylaminofluoran and 2-(2'-thenylamino)-8-dimethylbenz[c]fluoran, which are useful as a coloring material for record material systems, such as pressure-sensitive copying paper or heat-sensitive copying paper, wherein colored images formed by an electron-donor-acceptor color-forming reaction between coloring material and acidic material.

3 Claims, No Drawings

FLUORAN COMPOUNDS

This invention relates to a chromogenic compounds for use in recording sheet which develops color images by an electron donor-acceptor color-forming reaction between chromogenic material and acidic material which react upon contact to produce a color.

So far oil carbon paper was used for making out documents and slips as office work materials. It has drawbacks that it is liable to stain clothes and hands and it is troublesome to insert the oil carbon paper between documents and slips.

In order to eliminate the inefficiencies and defects of the oil carbon paper, pressure-sensitive copying paper or noncarbon paper, which is economic and handy, has recently made its debut in place of the oil carbon paper complying with demand for speed-up of office works.

Heretofore, leucoauramines, leucomethyleneblues, phthalides and fluorans are well known as color precursors. They are colorless or nearly colorless compounds, which may change to a certain coloring matter when they are brought into contact with acidic electron-acceptor as explained below.

For example, 2-methyl-6-diethylamino-fluoran having the following formula is one of the well-known color precursors which are colorless compounds under ordinary condition but change to red coloring matters by opening their lactone ring when they are brought into contact with acidic electron-acceptor.

The pressure-sensitive copying paper is usually prepared by coating a back side of one sheet of paper with a color precursor such as a leucoauramine or a fluoran, and coating a surface of another sheet of paper with an acidic electron-acceptor substance such as kaolin, bentonite, activated clay, acid clay, aluminum silicate, attapulgite, metal oxides, metal chlorides, metal sulfates, organic acids such as phenols, aliphatic acids or tannic acid, or phenolic resins such as p-phenylphenol-formaldehyde resin, p-cyclohexylphenylformaldehyde resin, etc. The pressure-sensitive copying paper is used by placing the coated papers upon one another so that the back side of the first paper may be faced to the surface of the second paper, and the back side of the second paper to the surface of the third paper and so on. By applying pressure or impact to the papers by means of a pencil, a ball-point pen or a typewriter on the first paper, the material on the back side and the electron acceptor substances on the surface of the papers are brought into contact with each other, whereby the colorless pressure-sensitive material moves to the electron-acceptor layer and undergoes color development and therefore colored images can be obtained.

The aforesaid compound has defects that, when used as color precursor for pressure-sensitive copying paper, it stains capsules in undesired red color because it is slightly soluble in water or slightly acidic or alkaline water.

Further, it has a relatively high vapor pressure so that it tends to vaporize from the capsules to form ghost images which contaminate regular images on the pressure-sensitive copying paper and to cause the images to disappear on the paper during storage for a long period of time.

Thus, an object of the present invention is to provide a novel chromogenic material without aforesaid defects.

This object can be accomplished by providing a novel fluoran represented by the following formula (I), (II), (III), or (IV),

wherein R_a and R_b each represents hydrogen atom, a lower alkyl group, a lower alkyl group substituted by halogen atom, lower alkoxy group or hydroxyl group, benzyl group or a benzyl group substituted by lower alkyl group, lower alkoxy group, halogen atom or nitro group as substituent R_1 ; R_c represents a general formula,

5

6

5

10

wherein R_2 , R_3 and R_4 each represents hydrogen atom, 15 a lower alkyl group, a halogen atom, a lower alkyl group substituted by halogen atom, lower alkoxy group or hydroxyl group, or phenyl group which may be substituted by lower alkoxy group, lower alkyl group, halogen atom or nitro group; R_5 represents hydrogen atom, 20 a lower alkyl group or an acyl group; R_6 and R_7 each represents hydrogen atom or a lower alkyl group; R_8 represents hydrogen atom, a lower alkyl group or benzyl group; R_9 and R_{10} each represents hydrogen atom, 25 a lower alkyl group, a lower alkoxy group, halogen atom, nitro group, amino group, an amino group substituted by lower alkyl group, lower alkoxy carbonyl group, a lower alkanesulfonyl group or benzenesulfonyl group which may be substituted by at least one R_1 ; R_{11} represents a lower alkyl group, a halogenated lower 30 alkyl group, an aralkyl group or an aralkyl group substituted by R_1 ; R_{12} and R_{13} represent hydrogen atom, a lower alkyl group, a halogenated lower alkyl group, phenyl group, aralkyl group, or phenyl or aralkyl group substituted by R_1 ; R represents hydrogen 35 or atom, a lower alkyl group, benzyl group or an acyl group; D represents a divalent radical, $-\text{O}-$, $-\text{S}-$ or

40

(R has the above-defined meanings); W represents D or $-\text{CH}_2-$; B represents pyridine or quinoline nucleus; P represents direct bond, or a divalent radical, 45 $-\text{O}-$, $-\text{S}-$,

R

(R has the above-defined meanings), $-\text{CH}_2-$, $-\text{CH}=\text{CH}-$ or $-\text{CH}_2-\text{CH}_2-$; q and r each are an integer provided that $q+r=3$ or 4).

R_d represents R_a or R_c , or represents R_m which is represented as follows; R_m represents a lower alkenyl group having 4 or less carbon atoms, a lower alkynyl group having 4 or less carbon atoms, or a group of the formula,

55

(R_1 is the same as defined above), wherein $q+r$ is 3 or 4; W is the same as defined above provided that W does not represent $-\text{CH}_2-$ in the case where A is benzene nucleus and $q+r=4$; n and n' is an integer of 1 to 7; t is an integer of 1 to 2; Y_1 represents hydrogen atom, a lower alkyl, a lower alkoxy, a halogen atom such as fluorine, chlorine, bromine and iodine, amino group, or an amino group substituted by at least one lower alkyl group or nitro group; Z stands for hydrogen atom, a lower alkyl, halogen atom such as fluorine, chlorine,

bromine and iodine, lower alkoxy, nitro or amino group, or an amino group substituted by at least one lower alkyl groups, or groups of the formula,

(wherein R_{14} and R_{15} each represents hydrogen atom, a lower alkyl, phenyl, halophenyl, methoxyphenyl or nitrophenyl); m is an integer of 1 to 4; A represents benzene or naphthalene nucleus, and Y_2 signifies phenyl, cyclohexyl, or benzyl group.

Throughout the present specification, the term "lower" as is seen in "lower alkyl group" indicates that the number of carbon atoms is from 1 to 4.

Acy group represents a group $R'-CO-$ in which R' is an alkyl group having 1 to 3 carbon atoms, or benzoyl group which may be substituted by an aliphatic group having 1 to 4 carbon atoms or by R_1 .

The present invention has technical advance over prior arts in the following points:

1. These fluoran compounds represented by the general formulas (I), (II), (III) and (IV) are colorless and stable in air at ordinary temperature, but the compounds (I), (II), (III) and (IV) change in color from white to red, green or black when they are brought into contact with an acidic electron-acceptor explained above.

2. These fluoran compounds (I), (II), (III) and (IV) show all sorts of dark colors, for example, deep red, dark green, dark blue-green, dark greenish black, or black according to the number, kind and position of substituents.

It is also possible to use the said compounds together with other color precursors such as C.V.L. (crystal violet lactone), B.L.M.B. (benzoyl leucomethylene-blue) or 2-tert-butyl-4-methyl-6-diethylaminofluoran, etc., to obtain a special color such as blue-black or black image on the paper without spoiling the other color precursors. These are significant features of the present invention.

3. These fluoran compounds are well soluble under colorless condition in a non-volatile non-polar solvent used for preparing a recording sheet. Examples of the non-polar solvent are as follows:

Cresylacetate, 1-phenyl-3-methyl-indane, 1,1-diphenylethane, bis-(α -methylbenzyl)benzenes; alkylated benzenes; alkylated naphthalenes such as dimethylnaphthalenes and dipropylnaphthalenes; mineral oil; paraffin oil; olive oil; and tricresyl phosphate, etc.

Good solubility particularly in the aromatic solvents makes it easy to prepare the recording sheet and to obtain a deep image on the paper.

4. The present fluoran compounds have no solubility and good stability in water, acids or alkalis. For example, 2-(5',6',7',8'-tetrahydro-2'-naphthylmethyl)amino-8-diethylamino-benz[c]fluoran can be boiled with an alkali solution without being destroyed.

5. The present fluoran compounds have good fastnesses to light, moisture and sublimation.

The obtained deep image on this recording sheet does not disappear or change in color by moisture or droplets of water, or by exposure to sun-light or by heating.

The recording sheet prepared with use of the present fluoran compound endures storage for a long period of time without the disappearance of the image on the documents and slips.

5 6. The present fluoran compounds have high color-developing speed. Such color formation occurs just at once when the fluoran compounds in the form of crystals or a solution in the above-cited solvents are brought into contact with the acidic electron-acceptor.

10 Then, the recording sheet prepared with use of the present fluoran compounds gives vivid deep images on the paper at the moment when a pressure or impact is applied onto the paper by means of a pencil, a ballpoint pen or a typewriter.

15 7. The images on the recording sheet prepared with
a mixture of the present fluoran compounds do not
change in color owing to the same color-developing
speeds caused by the same fluoran nucleus. The pres-
ent fluoran compounds represented by the general for-
20 mulas (I), (II), (III) and (IV) may be prepared by the
following methods.

In the presence of a dehydrating agent, fluorans (I), (II), (III) and (IV) can be prepared by reacting a α -(2'-hydroxyl-4'-aminobenzoyl)-benzoic acid represented by the formula

35 wherein R_I and R_{II} signify R_a , R_b , R_c , R_f , R_i and R_j , Z and m are defined above, with a compound represented by the formulas

wherein R_{III} and R_{IV} represent R_c , R_d , R_g , R_h , R_k and R_l . E stands for benzene, naphthalene or tetrahydro-naphthalene nucleus. R'' indicates hydrogen atom, a lower alkyl group or an acyl group, and R_k , R_l and Y_2 are as defined above, to obtain a fluoran represented by the following formulas,

pound having a stable lactone ring, white crystals are often obtained merely by neutralizing a hydrochloric acid or sulfuric acid solution thereof with caustic soda, potassium hydroxide, etc.

5 The second method is similar to the first method. Thus, a 2-(4'-amino-1'-hydroxy-2'-benzoyl)-benzoic acid represented by the formula,

10

15

wherein R₁, R_{II}, R_{III}, R_{IV}, R₅, R₆, R₇, R₈, R₉, Y₁, Y₂, Z, m and E are as defined above.

The reaction may be effected at a temperature of 0° to 300°C for several hours or sometimes for a few days in the presence of a dehydrating-condensing agent. Examples of the dehydrating-condensing agent include sulfuric acid; phosphorous pentoxide; phosphoric acid; polyphosphoric acid; anhydrous metal halides such as anhydrous tin chloride or bromide, anhydrous zinc chloride or bromide, anhydrous aluminum chloride or bromide, anhydrous ferric chloride or bromide; phosphoric pentachloride or bromide; phosphorous trichloride or bromide; phosphorus oxychloride or oxybromide, and anhydrous hydrogen chloride or fluoride.

If necessary, carbon disulfide, chlorinated benzenes, or nitrobenzenes are used as a solvent for the reaction.

After the reaction is over, the reaction mixture is poured into ice or water to separate solid, and if desired, the mixture is neutralized with a solution of an alkali such as caustic soda, potassium hydroxide and the like.

In order to convert the resulting solid to the pure fluoran compound represented by the formula (I), (II), (III) or (IV) by purification, the solid may be dissolved and heated in a solvent and then the mixture may be cooled or concentrated to obtain the fluoran compound (I), (II), (III) or (IV) as white crystals.

As a solvent for the purification, aromatic hydrocarbon solvents such as benzene, xylene, etc.; nuclear halogenated aromatic hydrocarbon solvents such as chlorobenzene, bromobenzene, dichlorobenzenes, trichlorobenzenes, etc.; alcohols such as methanol, ethanol, etc.; amide solvents such as dimethylformamide, diethylformamide, etc.; sulfoxide solvents such as dimethylsulfoxide, diethylsulfoxide, etc.; aliphatic hydrocarbon solvents such as n-hexane, cyclohexane, etc.; halogenated aliphatic hydrocarbon solvents such as chloroform, bromoform, methylchloroform, etc.; and ethers such as dimethyl ether, diethyl ether, etc. are useful.

The purification is often facilitated by the addition of an aliphatic amine such as dimethylamine, trimethylamine, diethylamine, triethylamine, etc.; an aliphatic aminoalcohol such as ethanolamine, propanolamine, etc.; or a heterocyclic basic substance such as pyridine, picoline, etc.

White crystals, which separate on heating and then cooling in any one of these purification solvents or a mixture thereof, are filtered and washed with a non-polar solvent such as cyclohexane, n-hexane, diethyl ether to obtain a colorless compound. In case of a com-

20 wherein R_{III}, R_{IV}, Y₁, Z, E and m are as defined above, may be reacted with a m-aminophenol at a proper reaction temperature in the presence of a dehydrating agent as explained above to obtain a fluoran compound.

The reaction proceeds as follows:

wherein R'', R₁, R_{II}, R_{III}, R_{IV}, Y₁, E, Z and m are as defined above. The purification procedure after the reaction is the same as that in the first method.

The third method is accomplished by the use of a fluoran compound prepared by the first or second methods. Thus, a aminofluoran represented by the formulas,

or

(wherein R_I , R_{II} , R_{III} , R_{IV} , Y_1 , E , Z and m are as defined above), which has at least one hydrogen atom in the amino substituent of the fluoran nucleus, is treated with an alkylating agent, an acylating agent or a sulfonylating agent as explained below in the presence or absence of a dehydrating agent or a dehydrohalogenating agent. The reaction is properly carried out at 0° – 200°C for several hours or sometimes for a few days, if desired, in the presence of a solvent such as benzene, toluene, xylene, chloroform, 1,2-dichloroethane, ether, dioxane, N,N -dimethylformamide, dimethylsulfoxide, alcohols, etc.

The reaction proceeds as follows:

(wherein R_I , R_{II} , R_{III} , R_{IV} , Y_1 , Z , m and E are as defined above, and X each signifies a residue of the alkylating, acylating or sulfonylating agent such as halogen atom, hydroxy group, SO_4^{2-} , PO_3^{3-} , etc.)

In the same way, a fluoran compound represented by the formula (III) may be obtained by reacting fluoran compound represented by the formula,

or

(wherein R_I , R_{II} , R_k , R_{III} , Y_2 , Z and m are as defined above), which has at least one hydrogen atom in the amino substituent, with an alkylating agent, an acylat-

ing agent or a sulfonylating agent as explained below. Examples of the acylating, alkylating and sulfonylating agents which may be used in the above-mentioned reaction include:

1. Acetic anhydride
- Propionic anhydride
- Butyric anhydride
- Propionic anhydride
- Crotonic anhydride
- Benzoic anhydride
- m-Chlorobenzoic anhydride
- m-Nitrobenzoic anhydride
- p-Bromobenzoic anhydride
- m-Methylbenzoic anhydride
- p-Methoxybenzoic anhydride
2. Acetyl chloride
- Propionyl chloride
- Acryloyl chloride
- Methacryloyl chloride
- Acetyl bromide
- Butyryl bromide
- Propiolyl bromide
- Crotonyl bromide
- Benzoyl chloride
- m-Chlorobenzoyl chloride
- p-Nitrobenzoyl chloride
- m-Bromobenzoyl chloride
- p-Methylbenzoyl chloride
- m-Methoxybenzoyl chloride
- Benzoyl bromide
- p-Chlorobenzoyl bromide
- m-Nitrobenzoyl bromide
- m-Methylbenzoyl bromide
- o-Methoxybenzoyl bromide

Also, as the alkylating agent, the following compounds are preferable.

3. Esters:
- Dimethyl sulfate
- Diethyl sulfate
- Dipropyl sulfate
- Trimethyl phosphate
- Triethyl phosphate
- Methyl benzenesulfonate
- Methyl p-toluenesulfonate
- Propyl p-toluenesulfonate
- Methoxyethyl p-toluenesulfonate
- Methoxypropyl p-toluenesulfonate
- Methyl methanesulfonate
- Propylmethanesulfonate

4. Lower alkyl halides:

- Methyl chloride
- Ethyl bromide
- Propyl chloride
- Butyl chloride
- 5. Benzyl halides:
- Benzyl chloride
- m-Nitrobenzyl chloride
- p-Chlorobenzyl chloride
- m-Bromobenzyl chloride
- p-Methylbenzyl chloride
- m-Methoxybenzyl chloride
- Benzyl bromide
- p-Nitrobenzyl bromide
- o-Bromobenzyl bromide
- m-Methylbenzyl bromide
- o-Methoxybenzyl bromide
- 6. Allyl halides:
- Allyl chloride

- 2-Methylallyl chloride
  - 2-Ethylallyl chloride
  - 2-Butenyl chloride
  - Cinnamyl chloride
  7. Propargyl halide derivatives:
  - Propargyl chloride
  - 2-Butynyl chloride
  - 2-Pentynyl chloride
  - 2-Pentynyl bromide
  - 3-Phenyl-2-propynyl bromide
  8. Oxiranes
  - Ethyleneoxide
  - Propyleneoxide
  - 2-Ethylloxirane
  - 2,2-Dimethyloxirane
  - 2,3-Dimethyloxirane
  - 2,2-Diethyl-3-methyloxirane
  - 2,2-Diphenyloxirane
  - 2-(4'-Nitrophenyl)-oxirane
  - 2-Phenylloxirane 2-(2'-Chlorophenyl)-oxirane
  9. Sulfonylating agents:
  - Methanesulfonyl chloride
  - Ethanesulfonyl chloride
  - Propanesulfonyl chloride
  - Butanesulfonyl chloride
  - Benzenesulfonyl chloride
  - p-Toluenesulfonyl chloride
  - m-Toluenesulfonyl chloride
  - p-Chlorobenzenesulfonyl chloride
  - o-Chlorobenzenesulfonyl chloride
  - m-Nitrobenzenesulfonyl chloride
  - o-Nitrobenzenesulfonyl chloride
  - m-Methoxybenzenesulfonyl chloride
- and bromides thereof such as, for example,
- Methanesulfonyl bromide
  - Ethanesulfonyl bromide
  - Benzenesulfonyl bromide
  - p-Toluenesulfonyl bromide
  - p-Chlorobenzenesulfonyl bromide
  - p-Nitrobenzenesulfonyl bromide
  - p-Methoxybenzenesulfonyl bromide

10. Miscellaneous

15

Colour precursor 1

16

As the dehydrohalogenating agent,
Sodium hydrogencarbonate
Potassium hydrogencarbonate
Sodium carbonate

30 Potassium carbonate
Sodium acetate
Potassium acetate
and

Caustic soda

35 may be used. Also if circumstances permit, the basic substance used in the purification, may be used.

As the solvent in the third method, aromatic hydrocarbon solvents such as benzene, xylene, etc.; halogenated aliphatic hydrocarbon solvents such as chloro-

40 form, bromoform, methylchloroform, etc.; halogenated aromatic hydrocarbon solvents such as chlorobenzene, bromobenzene, dichlorobenzenes, etc.; alcohol solvents such as methanol, ethanol, propanol, etc.; ether solvents such as diethyl ether, dimethylene glycol, di-
45 methyl ether, diethylene glycol, etc.; sulfoxide solvents such as dimethyl sulfoxide, diethyl sulfoxide, etc.; and amide solvents such as N,N'-dimethylformamide, di-
methylacetamide, N-methylpyrrolidone may be used.

50 Specific examples of the compounds of the general formulas (I), (II), (III) and (IV) produced by the above-mentioned methods according to the present invention which show excellent resistance to water, good fastness to light and rapid color developing speed are as follows. Shade on silica gel after development for each compound is also shown below.

2-[1'-(α -Ethylphenethyl)butylamino]-diethylaminobenz[c]fluoran	Green

As used in mark-forming systems, marking in desired areas on support webs or sheets may be accomplished by effecting localized reactive contact between the chromogenic material and the acidic material on or in such web or sheet, such chromogenic material being brought thereto by transfer, or already present therein, the reactive contact forming a clear coloration in the intended image-marking areas.

There have already been known several types of recording system utilizing an electron donor-acceptor color-forming reaction between chromogenic material and acidic material.

The pressure-sensitive recording systems generally comprise color-forming compounds on and/or within one or more sheet supports, the color-forming components being isolated from one another by a pressure-rupturable barrier. Where the color-forming components are disposed on separate sheets as disclosed in U.S. Pat. No. 2,712,507, the record material referred to as a "transfer" or "couplet" system. In such system, a solution of a chromogenic material is held in rupturable microscopic capsules coated onto one surface of

a transfer sheet, while an adjacent receiving sheet is sensitized with an acidic material, i.e., an electron acceptor. Most common acidic materials are activated acid clay and acid clays, such as attapulgite, zeolite, bentonite, kaolin and silica. Recently, monomeric phenols or acid reactant polymeric materials, such as phenolic polymers, phenol acetylene polymers, maleic acid-rosin resins, have been suggested either alone or in combination with acid clays.

- 10 In the manufacturing method of such record material, for instance, a non-volatile oil containing a chromogenic material dissolved therein is protected by encapsulation with coacervate film of a water-soluble polymer. The resulting coating composition containing dispersed capsules are coated on one side of a sheet, and coating composition of said electron acceptors is coated on the other side of the sheet. When several sheets are laid one over another and impressed with a pencil or the like. Capsules are collapsed to release the 20 oil containing chromogenic material which produces a duplicated image on contact with the electron-acceptor. In another system as disclosed in U.S. Pat. No. 2,730,457, a coating liquid containing both of the capsules chromogenic material and acidic material is 25 applied on one side of a sheet or alternatively, a coating containing capsules is first applied on one side of a sheet and the second coating containing the electron-acceptor is applied thereon. Thus, all the components are disposed on a single sheet, the record material is referred to as "self contained" system and develops 30 image color where the pressure is applied.

As a modification of pressure-sensitive marking system, Japanese Pat. No. 511,757 (corresponds to U.S. Pat. application Ser. No. 392,404, filed on Aug. 27, 1964) discloses a recording sheet, in which minute capsules containing liquid solvent are coated on one surface of a sheet support and both of the chromogenic material and the acidic polymer are coated on or im- 40 pregnated in same sheet or other sheet in solid condi- tion.

There is thermo-responsive record sheet as a mark-forming system utilizing an electron donor-acceptor color-forming reaction. For example, Japanese Pat. Pub. No. 14039/1970 (corresponds to U.S. Pat. application Ser. No. 554,565 filed on June 1, 1966) discloses a temperature-responsive record material comprising a supporting sheet material having crystal violet lactone and a phenolic material solid at room temperature but capable of liquefying and/or vaporizing at normal thermographic temperatures, said lactone and phenolic material being further capable of producing a mark-forming reaction upon reactive contact.

The novel compounds of our invention are widely used for above-mentioned mark-forming system as a colorless chromogenic compound, i.e., electron donor, and gives many excellent advantages.

According to the present invention, the above-mentioned known techniques for the production of the recording sheet are utilized using the above-mentioned fluoran compounds as a coloring material alone or in admixture with various known coloring materials to obtain the recording sheet which can form red, green or black color.

60 Also, it is effective for improving the color forming property and fastnesses to light and moisture of developed images to use a metal or metallic compound together with the electron-acceptor.

Thus, metals or metallic compounds such as manganese, nickel, cobalt, iron, zinc, copper, cadmium, mercury, silver, platinum, etc. are effective. Specific examples of the metallic compounds include salts and acid salts such as copper sulfate, ferrous sulfate, manganese sulfate, cobalt sulfate, zinc sulfate, nickel acetate, etc.; basic salts such as cadmium hydroxide; and oxides such as zinc oxide. They show particularly good results.

The present invention will be further specifically explained below referring to the following examples which do, of course, not limit the scope of the present invention.

EXAMPLE 1 (COLOUR PRECURSOR NO. 24)

140 Grams of 95 % sulfuric acid was charged into a four-necked flask. A mixture of 26.5 g of 2-hydroxy-5-amino-diphenyl hydrochloride and 31.3 g of o-(2'-hydroxy-4'-diethylaminobenzyl)-benzoic acid was added for one hour below 25°C. At that time, the hydrogen chloride gas evolved was absorbed in a absorber. After dissolution, the mixture was warmed to 25° to 30°C for 8 hours. After cooling, the reaction mixture was then poured into 1.5 kg of ice-water at 10° to 20°C. The mixture was neutralized with an aqueous caustic soda solution at the same temperature.

The precipitate was filtered and washed with water. The thus obtained crude solid, 2-amino-4-phenyl-6-diethylaminofluoran was dissolved in 500 g of benzene and dehydrated with 50 g of anhydrous sodium sulfate. After addition of 5 g of active charcoal, the benzene solution was filtered while hot. The filtrate was concentrated under reduced pressure to obtain the syrup. Thus, 2-amino-4-phenyl-6-diethylaminofluoran was obtained as white crystals. After recrystallization from benzene the compound had m.p. of 219.3°C.

The resulting compound formed dark reddish brown color on contacting with silica gel when used as a material for pressure-sensitive copying paper. The image having excellent fastnesses to moisture, sublimation and alkali was produced.

EXAMPLE 2 (COLOUR PRECURSOR NO. 8)

By use of the same procedure as in Example 1, 2-(1-pyrrolidinyl)-6-diethylaminofluoran was prepared from N-(4-hydroxyphenyl)-pyrrolidine and 2-(2'-hydroxy-4'-diethylaminobenzoyl)-benzoic acid. Yield: 41.8 %. Melting point: 238° - 240°C. This compound formed dark green color on silica gel with good fastnesses to light and moisture.

EXAMPLE 3 (COLOUR PRECURSOR NO. 17)

According to the same method as in Example 1, 2-[N,N-bis-(β-methoxyethyl)amino]-8-

diethylaminobenz[c]fluoran was prepared from N,N-bis-(β-methoxyethyl)-4-amino-1-naphthol and 2-(2'-hydroxy-4'-diethylaminobenzoyl)-benzoic acid. This derivative having a melting point of 195.3° to 196.3°C formed dark green color on silica gel.

EXAMPLE 4 (COLOUR PRECURSOR NO. 22)

On cooling with water in 300 cc flask, 25.3 g of 4-cyclohexylamino-1-naphthol was dissolved in 150 g of 90 % sulfuric acid below 20°C. Then at the same temperature, 31.3 g of 2-(4'-diethylamino-2'-hydroxybenzoyl)-benzoic acid was added. After completion of the dissolution, the reaction mixture was stirred for 15 hours between 20°C and 30°C. After the reaction was over, the reaction content was poured into 1.5 kg of ice-water mixture at about 0°C. After neutralized and set the pH to 11 with sodium hydroxide solution, the obtained crude solid was filtered, the solid was recrystallized repeatedly 26 g of 2-cyclohexylamino-8-diethylamino-benz[c]fluoran was obtained as white crystals having a melting point of 272.2°C. This compound formed dark green color on silica gel and did not change in color during storage for a long period of time.

EXAMPLE 5 (COLOUR PRECURSOR NO. 23)

In the same way colour precursor No. 23, 2-cyclohexylamino-6-diethylaminofluoran was obtained from N-cyclohexyl-p-anisidine and 2-(4'-diethylamino-2'-hydroxybenzoyl)-benzoic acid. This compound formed greenish black colour on silica gel and had a good fastness to light and moisture. m.p.: 212.2° - 213.2°C

EXAMPLE 6 (COLOUR PRECURSOR NO. 27)

Colour precursor No. 27, 2-amino-8-diethylamino-3,4,5,6-tetrahydro-benz[c]fluoran was prepared with 4-amino-5,6,7,8-tetrahydro-1-naphthol and 2-(4'-diethylamino-2'-hydroxybenzoyl)-benzoic acid. This compound, having a melting point of 242.1°C gave reddish brown colour on silica gel.

EXAMPLE 7 (COLOUR PRECURSOR NO. 20)

2-[N,N-bis-(β-methoxyethyl)amino]-6-diethylaminofluoran prepared from N,N-bis-(β-methoxyethyl)-p-anisidine was obtained as white crystals, m.p. = 95.3°C. This derivative gave dark green colour on silica gel and good light fastness.

EXAMPLE 8

In the same manner as in Example 1, the following compounds were synthesized. Shade on silica gel is shown on the right hand column.

EXAMPLE 9 (COLOUR PRECURSOR NO. 1)

13.0 Grams of 2-amino-8-diethylaminobenz[c]-fluoran and 8.0 g of 1-chloromethyl-naphthalene were maintained in 70 g of N,N-dimethylformamide at 70° to 80°C in the presence of sodium carbonate for 5 hours. The reaction mixture was then poured into ice-water to form precipitate, which was filtered and extracted with benzene. The benzene solution was washed with aqueous sodium carbonate solution and then with water several times and dried over anhydrous sodium sulfate. The extract was concentrated to obtain a syrupy product which was then filtered.

Thus, 2-(1'-naphthylmethylamino)-8-diethylaminobenz[c]fluoran was obtained as white crystals. Yield: 45.6 %. The product was recrystallized from benzene. The resulting crystals showed a melting point of 242° - 244°C. This compound formed dark green color on silica gel.

EXAMPLE 10 (COLOUR PRECURSOR NO. 4)

The same procedure as in Example 9 was repeated by using α -chloroethylbenzene and 2-amino-8-diethylaminobenz[c]fluoran. Thus, 2-(α -methylbenzyl)-amino-8-diethylaminobenz[c]fluoran was obtained as white crystals having a melting point of 130° to 133°C. This compound gave green colour on silica gel.

EXAMPLE 11 (COLOUR PRECURSOR NO. 5)

10 In the same manner as in Example 9, 2-[N-methyl-N-(5,6,7,8-tetrahydro-2-naphthylmethyl)amino]-6-diethylaminofluoran was obtained from 2-chloromethyl-5,6,7,8-tetrahydronaphthalene and 2-amino-6-diethylaminofluoran. This compound formed 15 dark green color on silica gel.

EXAMPLE 12

In the same manner as in Example 7, the compounds of the following formulas were obtained. Shade on silica gel is shown in the right hand column.

Starting material	Reagent	Product	Colour
	$\text{ClCH}_2\text{--}\text{C}_6\text{H}_4\text{--S--C}_6\text{H}_5$		Dark green

EXAMPLE 13

10 Grams of 2-amino-4-phenyl-6-diethylaminofluoran was heated at about 140°C for 3 hours together with 30 g of acetic anhydride. After the reaction was completed, the unreacted acetic anhydride was removed by steam distillation to form a solid which was filtered. The solid was then recrystallized from chloroform. Thus, 2-acethylamino-4-phenyl-6-diethylaminofluoran by the formula,

was obtained in a yield of 63.2 %. This compound formed red color on silica gel.

EXAMPLE 14

According to the procedure similar to that of Example 10, 2-(p-toluenesulfonylamino)-8-diethylamino-3,4,5,6-tetrahydro-benz[c]fluoran represented by the formula,

50 was obtained as white crystals from 13.8 g of 2-amino-8-diethylamino-3,4,5,6-tetrahydro-benz[c]fluoran and 8.5 g of p-toluenesulfonyl chloride in N,N-dimethylformamide. This compound gave red colour on silica gel.

EXAMPLE 15 (COLOUR PRECURSOR NO. 18)

55 In a mixed solvent of ethanol (60 g) and acetic acid (12.6 g), 4 g of 2-methylamino-6-diethylaminofluoran was dissolved. At about 45°C, 6.4 g of propylene oxide was dropped. After the starting material was disappeared the reaction mixture was discharged into 1.0 kg of water, followed by neutralization the obtained crude solid was filtered and then recrystallized with benzene. m.p. = 137.8°C. This compound gave dark green colour on silica gel.

EXAMPLE 16 (COLOUR PRECURSOR NO. 21)

In the similar method with Example 15, colour precursor No. 21 was obtained, as white crystal having a melting point of 85.0° to 86.0°C.

EXAMPLE 17 (COLOUR PRECURSOR NO. 19)

A mixture of 4.0 g of 2-methylamino-6-diethylaminofluoran and 23.0 g of β -methoxyethyl *p*-toluenesulfonate in 20 g of N,N-dimethylformamide was maintained at 75° to 95°C in the presence of sodium bicarbonate till the starting material was disappeared. The reaction mixture was then poured into 1,000 g of cold water to separate a solid which was dissolved in 200 g of benzene. The benzene solution was washed with a dilute aqueous Na_2CO_3 solution and with water several times and dried over anhydrous sodium sulfate. The solution was then concentrated under reduced pressure to form white crystals which were filtered. Thus, colour precursor No. 19, 2-(N-methyl-N- β -methoxyethyl)amino-6-diethylaminofluoran having a melting point of 126.4°C was obtained in a yield of 48 %. This compound formed green colour on silica gel.

EXAMPLE 18

In the same manner as in Example 10, the compounds of the following formulas were obtained. Shade on silica gel is shown in the right hand column.

EXAMPLE A

In 200 g of 1,1-diphenylethane was dissolved 6 g of colour precursor No. 1. The resulting solution was mixed vigorously at 40°C with 360 g of a 11.0 % aqueous gelatin solution to make an emulsion. To the resulting emulsion, 300 g of a 10 % aqueous gum arabic solution was added. Acetic acid was added to the mixture at 40°C with stirring to adjust the pH value to 5, and water was then added to effect the coacervation of the system, whereby oil droplets containing the above-mentioned benz[c]fluoran compound were coated by the coacervated liquid wall of a complex of gum arabic and gelatin. At 5°C, the pH value of the system was further reduced to 4.4 and 5 g of 35 % formalin was added to harden the wall. In order to complete micro-encapsulation, 10 % sodium hydroxide was added to increase the pH value to 9 and the whole system was then gradually warmed to 50°C. The coating composition containing the thus prepared microcapsules was applied onto paper in a conventional manner. This paper was faced to the second paper onto which active clay or a phenylphenolformaldehyde resin had been applied together with a binder. A dark green image was

Starting material	Reagent	Product	Colour
	$\text{ClCO}-\text{C}_6\text{H}_5$		Red
	$\text{CH}_3-\text{CH}_2-\text{CH}_2-\text{O}-$		"
	$\text{CH}_3-\text{C}_6\text{H}_4-\text{SO}_2-\text{OCH}_2-\text{CH}_2\text{OCH}_3$		Green
	$\text{CH}_2=\text{CH}-\text{CH}_2\text{Cl}$		Green

instantly formed on the second paper by applying pressure by means of a pencil. The thus obtained green image did not change in colour and showed good fastnesses to light, water and heat.

EXAMPLE B

According to a procedure similar to that of Example A, similar pressure-sensitive copying paper was prepared from 6 g of colour precursor No. 2. Red image was obtained by the application of pressure by handwriting. The thus obtained red colour had good fastnesses to light, water and heat.

EXAMPLE C

According to the same procedure as that of Example A, similar pressure-sensitive copying paper was prepared from 6.0 g of colour precursor No. 3. With a pressure of a typewriter, deep green image was obtained. The thus obtained deep green colour had good resistances to light, water and heat.

EXAMPLE D

In the same manner as in Example A, pressure-sensitive copying paper was produced by using colour precursor No. 5, as an electron donating colour former and activated clay as an electron-acceptor substance. Dark green copied image obtained on the electron-acceptor-coated surface had good fastnesses to light and water.

EXAMPLE E

In the same manner as in Example A, pressure-sensitive copying paper was prepared using colour precursor No. 7 as an electron donating colour former and activated clay as an electron-acceptor. Copied image obtained on the electron acceptor-coated surface was dark green in colour and showed excellent fastnesses to light and moisture like that of Example A.

EXAMPLE F

Pressure-sensitive copying paper was prepared in the same manner as in Example A except that 3 parts by weight of colour precursor No. 8 and 3 parts of colour precursor No. 11 which may form dark red colour, as electron donating colour formers were dissolved in 100 parts by weight of cresylacetate. Copied image obtained on the electron-acceptor surface was black in colour and maintained the original colour during storage for a long period of time.

EXAMPLE G

Pressure-sensitive copying paper was prepared in the same manner as in Example A except that 3 parts by weight of colour precursor No. 13, and 3 parts by weight of 2-tert-butyl-4-methyl-6-diethylaminofluoran, which may form red colour, as electron donating colour formers were dissolved in 100 parts by weight of 1,1-diphenylethane. Copied image obtained on the electron-acceptor coated surface was black in colour and maintained the original shade during storage for a long period of time.

EXAMPLE H

Pressure-sensitive copying paper was prepared in the same manner as in Example A except that 3 parts by weight of colour precursor No. 14 and 3 parts by weight of colour precursor No. 18, which may form dark green colour, as electron donating colour formers were dissolved in 100 parts by weight of 1-phenyl-3-methyl-indane. Copied image obtained on the electron-acceptor coated surface was black in colour and maintained the original shade during storage for a long period of time.

EXAMPLE I

Pressure-sensitive copying paper which may form black colour images was obtained in the same manner as in Example A except that 3 parts by weight of colour precursor No. 16 and 3 parts by weight of 4-methyl-2-tert-butyl-diethylaminofluoran were used as electron donating colour formers obtained image was black in colour which had good fastness to sun light.

EXAMPLE J

In 100 parts by weight of 1,1-diphenylethane, 4 parts by weight of colour precursor No. 19 was dissolved at 100°C. The colour former-containing oil was dispersed in a mixture of 500 parts by weight of a 10 % gelatin solution and 500 parts by weight of a 10 % gum arabic solution at 60°C to form an emulsion. Then, 1,000 parts by weight of warm water at 40°C was added to dilute the emulsion.

A 10 % acetic acid solution was gradually added dropwise at 50°C with stirring to adjust the pH value to 4 - 4.3. The emulsion was cooled to a temperature below 15°C. At this temperature, 500 parts by weight of a 20 % dispersion of titanium oxide having a particle size of 0.2 to 0.4 μ was added and 100 parts by weight of a 10 % formalin was then added. Further, 10 % caustic soda was gradually added dropwise to adjust the pH value to 10 - 10.5. The thus obtained dispersion is referred to as "A liquid."

On the other hand, 40 parts by weight of 10 % caustic soda and 200 parts by weight of activated clay were dispersed in 400 parts by weight of water. Then, 200 parts by weight of a 10 % polyvinyl alcohol was added. The thus obtained dispersion was uniformly mixed with the above-mentioned A liquid to obtain a coating composition.

The coating composition was applied onto one side of 40 g/m² paper in an amount of 7 g/m² on dry basis and then dried. The resulting pressure-sensitive copying paper in a "self contained" type. When pressure was applied onto the coated surface, dark green colour was formed which did neither change nor disappear on exposure to light or moisture.

EXAMPLE K

By the same procedure as in Example A, similar pressure-sensitive copying paper was obtained from the following colour precursors. The properties and fastnesses of the pressure-sensitive copying paper were the same as in Example A.

EXAMPLE L

The capsule-containing coating liquid as prepared in Example A was applied onto one side of 45 g/m² paper in an amount of 5 g/m² on dry basis and dried. Further, the electron-acceptor containing coating liquid as prepared in Example A was applied onto the coated surface in an amount of 4 g/m² and dried. The resulting pressure-sensitive copying paper is a self-contained type containing both a colour former capsule-coated layer and an electron-acceptor-coated layer on one side of the paper.

Good pressure-sensitive copying paper can be prepared by replacing the electron-acceptor-containing coating liquid used in the above-mentioned examples by coating liquids of the following recipes:

		Parts by weight
(a)	Water	100
	Acid clay	100
	Cadmium hydroxide	10
	Styrene-butadiene latex	20
(b)	Water	200
	Acid clay	100
	Manganese sulfate	5
	Styrene-butadiene latex	15
(c)	Water	200

	Acid clay	100
	Nickel sulfate	5
	Latex	15
(h)	Water	200
	Attapulgite	100
	Zinc oxide	5
	Latex	15

EXAMPLE M

In 100 parts by weight of bis(α -methylbenzyl)benzene, 4 parts by weight of colour precursor No. 22 was dissolved at 100°C. The colour former-containing oil was dispersed in 500 parts by weight of a 7% gelatin solution at 60°C to form an emulsion. To the emulsion, 350 parts by weight of a 10% gum arabic solution was added and 550 parts by weight of warm water was added. A 10% acetic acid solution was gradually added dropwise at 50°C with stirring to adjust the pH value to 4.0 – 4.3 and the emulsion was cooled to a temperature below 10°C. 200 Parts by weight of a 50% dispersion of titanium oxide having a particle size of 0.2 to 0.5 μ was gradually added at this temperature with stirring. 15 38 Parts by weight of 37% formalin was then added and a 10% caustic soda solution was added dropwise to adjust the pH value to 10.0 to 10.5. The thus obtained dispersion is referred to as "A liquid."

On the other hand, 20 parts by weight of zinc oxide and 40 parts by weight of a 28% ammonia water was added to 400 parts by weight of water. Then, 200 parts by weight of acid clay was dispersed in the mixture and one part by weight of sodium alginate was added. Further, 100 parts by weight of a 10% polyvinyl alcohol 25 solution was added and the whole was well mixed. The resulting dispersion was mixed with the above-mentioned A liquid and 250 parts by weight of a 10% polyvinyl alcohol solution and 100 parts by weight of pulp powder to form a coating composition.

30 This coating composition was applied onto one side of 40 g/m² paper in an amount of 10 g/m² dry basis and dried. The thus obtained pressure-sensitive copying paper is a so-called self-contained type copying paper. Dark green image could be instantly formed by the application of pressure and the obtained image did neither change in colour nor disappear on exposure to light or moisture.

EXAMPLE N

40 Similar pressure-sensitive copying paper could be prepared by replacing used in Example M by the following fluoran compounds. Shade of the image obtained is shown in the right hand column.

EXAMPLE 0

A thermo-responsive (or heat-sensitive) recording material is manufactured by following manner. 20 Parts by weight of colour precursor No. 25, 15 parts by weight of colour precursor No. 28, 150 parts by weight of a 10 % aqueous solution of polyvinyl alcohol, and 65 parts by weight of water were dispersed in high shear mixer. (Component A). 35 Parts by weight of Bisphenol A, 150 parts by weight of the polyvinyl alcohol solution, and 65 parts by weight of water were dispersed in high shear mixer. (Component B). 3 Parts by weight of Component A and 67 parts by weight of Component B were combined and coated on the paper sheet at a dry weight of 5 g/m². Resulting sheet may be used alone as a copy-receiving sheet by being served with a pattern of heat from front or back, as by a thermographically-heated original document, by trace of a hot stylus, by hot type, or by any other means giving a heat pattern by conduction. Developed image of this sheet is clear black. 40 45 50

What is claimed is:

1. A compound of the formula

wherein R_0 is selected from the group consisting of

2. 2-(2'-Benzylcyclohexylamino)-8-diethylaminobenz[c]fluoran.
 3. 2-Cyclohexylamino-8-diethylaminobenz[c]fluoran.
